LINK CHAIN FOR A BRACELET OR THE LIKE

Emil Rodriguez, New York, N. Y., assignor to
Jacoby-Bender, Inc., New York, N. Y., a corpora-
tion of New York

Application November 3, 1951, Serial No. 17,268

Term of patent 7 years

(Cl. D45—16)

To all whom it may concern:

Be it known that I, Emil Rodriguez, a citizen of the United States and a resident of New York, county and State of New York, have invented a new, original, and ornamental Design for a Link Chain for a Bracelet or the like, of which the following is a specification, reference being had to the accompanying drawing, forming a part thereof, in which:

Fig. 1 is a top view of the link chain, showing my new design;

Fig. 2 is a top plan view of one of the links of the chain;

Fig. 3 is an end elevational view of the link of Fig. 2, taken from the lower end thereof; and

Fig. 4 is a side elevational view of the link of Fig. 2, taken from the lefthand side thereof.

I claim:

The ornamental design for a link chain for a bracelet or the like, as shown.

EMIL RODRIGUEZ.
